UNITED STATES PATENT OFFICE.

JOHN B. CLEAVELAND AND CHARLES HERDRICH, OF INDIANAPOLIS,
INDIANA; SAID HERDRICH ASSIGNOR TO SAID CLEAVELAND.

MACHINE FOR MAKING TWISTED-WIRE STRANDS.

SPECIFICATION forming part of Letters Patent No. 579,563, dated March 30, 1897.

Application filed July 13, 1895. Serial No. 555,936. (No model.)

To all whom it may concern:

Be it known that we, JOHN B. CLEAVELAND and CHARLES HERDRICH, citizens of the United States, residing at Indianapolis, in the county of Marion and State of Indiana, have invented certain new and useful Improvements in Machines for Making Twisted-Wire Strands; and we do hereby declare the following to be a full, clear, and exact description of the invention, such as will enable others skilled in the art to which it appertains to make and use the same.

Our invention relates to improvements in machines for making fence-wire, and has for its object the construction of a machine to automatically produce a twisted-wire fence-strand consisting of four wires, which are first twisted together in pairs and then the said pairs twisted together to form a single strand having the general appearance of a four-wire braided strand such as was patented to John B. Cleaveland July 10, 1894, No. 522,826.

We accomplish the objects of the invention by the mechanism illustrated in the accompanying drawings, in which like letters refer to like parts throughout the several views.

Figure 1 is a view in perspective of our complete machine; Fig. 2, a detail showing the under side of the front end of the bed-plate of the machine and attached parts; Fig. 3, a detail in elevation of the wheels for giving the proper tension to the finished wire before it is reeled, and the figure shows the standards for supporting the wheels; and Fig. 4 is a detail showing the wire produced by the machine.

A represents the bed-plate of the machine, and a the legs on which the bed-plate rests.

B is a transverse shaft mounted in the journal-boxes b on the under side of the bed-plate. (See Fig. 2.)

B' is a pulley secured to the outer end of the shaft B and is driven by the belt B².

C is a bevel-pinion which is mounted on the inner end of the driving-shaft B and projects through a slot in the bed-plate.

C' is a large bevel-wheel mounted on the top of the bed-plate and intermeshing with the bevel-pinion C. The wheel C' is mounted on a suitable short vertical shaft c. Formed integral with or secured to the upper side of

the bevel gear-wheel C' are the two radially-aligned guideways d, within which are secured the radially-adjustable slides D, which form the seats for the vertical shafts D'. Mounted upon the upper ends of the vertical shafts D' are the wire-carriers D², which revolve with the vertical shafts, or if it is preferred to make the shafts D' stationary with reference to their supports then the wire-carriers will revolve around the said shafts.

D³ are sprocket-wheels of equal size mounted on the shafts D', whereby the rotation of said wheels will transmit a rotary movement to the wire-carriers.

E is a sprocket-wheel mounted on the upper end of the shaft c. The shaft c and the wheel E are both fixed and stationary.

E' is a sprocket-chain extending around the two sprocket-wheels D³ and around the wheel E, whereby when the bevel gear-wheel C' is rotated and the wheels D³ carried around the fixed wheel E the wheels D³ will be rotated around their individual axes by the action of said belt, but in opposite directions to the movement of the wheel C'. The diameters of the wheels D³ are each the same and are just one-half of the diameter of the stationary wheel E. This is an essential feature in the construction of our machine for the reasons as will be hereinafter fully pointed out. The wire-carriers D² being secured to the wheels D³ will also be revolved with said wheels. Mounted on each of the wire-carriers are the two bobbins F F, carrying the wire.

D⁷ is a cross-bar supported by the standards d², which are integral with the carriers, and d⁸ is an opening through the bar forming a twisting-plate through which the two wires from the pair of bobbins mounted on that wire-carrier are threaded in the manner clearly shown in Fig. 1.

C³ are vertical standards secured to the wheel C' and projected upwardly a suitable distance above the cross-bars D⁷ on the wire-carriers.

C' is a cross-bar connecting the tops of the standards C³ and supported by the said standards. It has an opening through which the twisted wires from the wire-carriers D² are threaded.

By making the diameters of the wheels D³

- just one-half of the diameter of the stationary wheel E the twisting-bars D⁷ will be given twice the speed of the twisting-bar C⁷ and will revolve in a direction opposite to the bar C⁷.
- 5 One-half of the double speed of the bars D⁷ is made necessary by the rotary movement of the bars around a common center in a direction which counteracts half of the twist that would otherwise be given to the wires as they 10 come from the bars D⁷. The result is that the twist given to the two wires forming the two-part strands as they come from the bars D⁷ is the same in degree but in opposite direction as the twist given by the bar C⁷ to the two 15 two-part strands and enables us to combine the four wires of the finished cable together in such a manner that all four of the wires can be seen at regular intervals in their full thickness—that is, without overlapping and 20 obstructing the view of each other. By this means we are able to produce a more ornamental and bulkier cable than by any other means.
- G is a curved standard which is fastened to 25 the top of the bed-plate and is projected upwardly in the manner as clearly shown in Fig. 1. G' is a transverse horizontal shaft mounted on the upper end of the said standard, and G² is a grooved wheel over which the wire from 30 the eye in the bar C⁷ passes. The bottom of the groove in the wheel G² is irregular, the irregularities being made to fit the contour of the twisted fence-strand, so as to secure a hold on the wire and keep it drawn sufficiently 35 taut.
- H, H', and H² are vertical standards secured to the bed-plate, and H³ is a horizontal shaft mounted on suitable box-bearings secured to the said standards.
- 40 I is a shaft mounted parallel with the shaft H³ on box-bearings secured to the standards H and H', but secured so as to be adjustable vertically and being pressed down by the springs g, as shown in Fig. 3. The gear-wheel h is mounted on the shaft H³, and the gear-wheel i is mounted on the shaft I, and the two gear-wheels intermesh with each other, whereby 45 when the shaft H³ is rotated the shaft I will be actuated also.
- 50 I' is a grooved wheel mounted on the shaft I, and I² is a disk mounted on the shaft H³ and working into the groove in the wheel I'. The periphery of the disk is corrugated and the bottom of the groove in the wheel is irregular, whereby the wire strand from the wheel G² (which strand is passed between the wheel I' and the disk I²) is grasped and drawn upon with a tension regulated by the speed of the said wheel and disk.
- 55 As the prime object of this invention is to produce a four-strand wire having the greatest possible bulk as distinguished from a compact wire, we find it necessary to carefully regulate the speed of the wheel G² with relation to the speed of the underlying mechanism for twisting up the wires, in order that 60 the two primary strands will be brought to-

gether in the right position at the moment of uniting them. To insure this nicety of action, the depressions in the groove of the 70 wheel G² are shaped and spaced to take the swells of the wire with much the same regularity that the sprockets of a wheel take the links of a chain belt. The wire as it comes from the twisting-plates is held from slipping, and the speed of the wheel G², regulated 75 properly to the speed of the twisting machinery, insures the proper tension and take-up of the wire strands to bring them together just right.

80 M is a sprocket-wheel mounted on the shaft H³, and m is a chain belt connecting the wheel M with the sprocket-wheel G³ on the shaft G', so that the shaft G' will be driven from the shaft H³.

M' is a sprocket-wheel on the shaft H³ and is connected by the chain belt M' with the small sprocket-wheel N on the shaft N'.

85 N² is a large sprocket-wheel on the outer end of the shaft N' and is connected by the 90 chain belt O with the small sprocket-wheel O' on the shaft O², (see Figs. 1 and 2,) and O³ is a large sprocket-wheel on the shaft O², which is connected by means of the chain belt b² with the small sprocket-wheel b³ on 95 the driving-shaft B. Thus it will be seen that the shaft H³ is driven from the shaft B through suitable intermediate gearing whereby the speed will be properly reduced to suit the requirements for the shaft H³.

100 R is a shaft mounted on suitable bearings secured to the bed-plate. It is provided at one end with a sprocket-wheel R', which is connected by the chain belt R² with the sprocket-wheel R³ on the shaft H³.

105 S is a reel upon which the finished wire is wound. It is mounted on the end of the shaft R opposite the end on which the wheel R' is mounted.

110 T is a feed of any desired or usual construction for delivering the wire uniformly to the reel S. Its sprocket-wheel t is driven by the belt R² in the manner clearly shown in Fig. 1.

Having thus described our invention, what we claim as new, and wish to secure by Letters 115 Patent, is—

1. In a wire-twisting machine, the combination, of a bed-plate, a fixed shaft secured to said bed-plate, a stationary sprocket-wheel mounted on said fixed shaft, a revolute wheel mounted on said shaft between the fixed wheel and the bed-plate, a twisting-plate supported in an elevated position on standards projected up from the revolute wheel and moving therewith, means for actuating 120 said revolute wheel, a pair of revolute wire-carriers mounted on diametrically opposite sides of said revolute wheel and having sprocket-wheels one-half the diameter of the 125 stationary sprocket-wheel fixed to each of said carriers, a sprocket-chain connecting the stationary sprocket-wheel with the sprocket-wheels on the wire-carriers, a pair of revolute bobbins mounted on each of said wire-

carriers, having the wire to be twisted, wound thereon, a twisting-plate for each pair of bobbins mounted on upwardly-projected extensions of the carriers and revolving with their respective carriers, said plates being below the first-mentioned twisting-plate, and wires wound on the spools and threaded from each group of spools, through the nearest twisting-plate and from thence through the top twisting-plate, all substantially as described and for the purposes specified.

2. In a wire-twisting machine, the combination, of a bed-plate, a fixed shaft secured to said bed-plate, a stationary sprocket-wheel mounted on said fixed shaft, a revolute wheel mounted on said shaft between the fixed wheel and the bed-plate, a twisting-plate supported from the revolute wheel and moving therewith, means for actuating said revolute wheel, a pair of revolute wire-carriers mounted on diametrically opposite sides of said revolute wheel and having sprocket-wheels one-half of the diameter of the stationary sprocket-wheel fixed to each of said carriers, a sprocket-chain connecting the stationary sprocket-wheel with the sprocket-wheels on the carriers, a pair of revolute

bobbins mounted on each of said wire-carriers, having the wire to be twisted, wound thereon, a twisting-plate for each pair of bobbins mounted on upwardly-projected extensions of the carriers and revolving with their respective carriers, said plates being below the first-mentioned twisting-plate, wires wound on the spools and threaded from each group of spools through the nearest twisting-plate and from thence through the top twisting-plate, means consisting of a grooved wheel with irregularities in the width and depth of the groove to fit the contour of the wire, belt connection from the grooved wheel to the driving-shaft of the machine to insure a determined ratio of speed between the wheel and the wire-twisting mechanism, and mechanism for reeling up the wire as it is made, all substantially as described and specified.

In testimony whereof we affix our signatures in presence of two witnesses.

JOHN B. CLEAVELAND.
CHARLES HERDRICH.
